[57] CLAIM

The ornamental design for a portable electronic computer for bowling, as shown and described.

DESCRIPTION

FIG. 1 is a front elevational view of the portable electronic computer for bowling showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a bottom, front and left side perspective view thereof.

The broken lines are shown in the figures for illustrative purposes only and form no part of the claimed design.

FIG. 1

FIG. 2

FIG. 3

FIG. 4

FIG. 5

FIG. 6
